UNITED STATES PATENT OFFICE

122,421

DESIGN FOR A TOP UNIT FOR BACK BARS OR THE LIKE

Clarence W. Shangle, Chicago, Ill., assignor to
The Brunswick - Balke - Collender Company,
Chicago, Ill., a corporation of Delaware

Application June 24, 1940, Serial No. 93,206

Term of patent 3½ years

To all whom it may concern:

Be it known that I, Clarence W. Shangle, a citizen of the United States, residing in the city of Chicago, in the county of Cook and State of Illinois, have invented a new, original, and ornamental Design for a Top Unit for Back Bars or the like, of which the following is a specification, reference being had to the accompanying drawing, forming a part thereof.

unit for back bars or the like, showing my new design.

I claim:

The ornamental design for a top unit for back bars or the like, as shown.

CLARENCE W. SHANGLE.
